UNITED STATES PATENT OFFICE.

CALVIN ALLEN BUFFINGTON, OF BERKSHIRE, NEW YORK.

FOLDING CHAIR.

Continuation of application Serial No. 485,246, filed July 16, 1921. This application filed November 27, 1922. Serial No. 603,452.

To all whom it may concern:

Be it known that I, CALVIN A. BUFFINGTON, being a citizen of the United States, residing at Berkshire, in the county of Tioga and State of New York, have invented certain new and useful Improvements in Folding Chairs, of which the following is a full, clear, and exact description.

This invention relates to chairs. More specifically it relates to folding chairs, i. e., to chairs having relatively movable parts adapted to be moved from occupant-supporting position to a collapsed or folded position, and vice versa.

One of the important objects of the invention is to provide a folding chair in which the constituent parts may be folded into a compact form so that a large number of such chairs may be stored in comparatively small space.

Another object is to provide a folding chair which is comparatively simple in construction and easy to operate.

A further object is to provide a folding chair certain of the frames or parts of which are made of bent wood.

A still further object is to provide a folding chair having a small number of relatively moving parts and all of which parts are movable to a position substantially within the bounding front and rear planes of a main frame constituting one of the parts. Other objects and advantages will appear as the invention is hereinafter disclosed.

Referring to the drawings which illustrate what I now consider a preferred form of the invention,

Fig. 1 is a side elevation of one form of the chair in condition to support an occupant.

Fig. 1^a is a detail side elevation illustrating a modification of certain of the parts shown in Fig. 1.

Fig. 2 is a plan view of the chair shown in Fig. 1.

Fig. 3 is a rear elevation of the chair shown in Fig. 1.

Fig. 3^a is a detail elevational view of a form of rear leg structure and main frame slightly different from those shown in Fig. 3.

Fig. 4 is a sectional elevation taken substantially on the line 4—4 of Fig. 3.

Fig. 5 is an enlarged detail section taken substantially on the line 5—5 of Fig. 1.

Fig. 6 is a rear elevation of the chair shown in Fig. 1 but illustrating the chair in folded position.

Fig. 7 is a sectional elevation taken substantially on the line 7—7 of Fig. 6.

Fig. 8 is a section taken substantially on the line 8—8 of Fig. 6.

Referring to Figs. 1, 2 and 3, it will be seen that the folding chair there illustrated comprises a main frame 10, a seat frame 11 and rear legs 26. The main frame 10 is preferably constructed of a single straight strip of oak or other suitable wood bent by any well known method such as steaming to form a U-shaped member of which the U-bend 13 constitutes a back rest, or one of the members of a back rest, for a person sitting upon the chair. The lower extremities or legs of the U-shaped main frame are adapted to form two of the legs of the chair. To impart rigidity to the main frame 10 the latter may be provided with a cross brace 14 suitably connected, as by means of mortise and tenon joints, at its opposite ends to the legs of the main frame. This brace 14 may also be employed as a foot rest by a person seated behind the chair. It will be understood of course that if the main frame is constructed of bent-wood as described, the grain of the wood will run generally in the shape of the U, i. e., the grain will extend longitudinally of the bend 13 as well as longitudinally of the legs of the U.

The seat frame 11 is also preferably constructed of a single straight strip of oak or other suitable wood, bent to form a U-shaped member. The inside of the U-shaped seat frame is shown provided with a groove 15 adapted to receive the edge of a seat 16 which is preferably padded or upholstered as indicated at 17.

The seat frame 11 is preferably pivoted within the main frame 10 so as to be movable from the occupant-supporting position shown in Fig. 1 to the folded position within the main frame as shown in Figs. 6 and 7. This pivotal connection is preferably effected by means of a metallic rod 18 which passes through the sides of the main frame and through the sides of the seat frame. The portions of the opposite ends of the rod 18 which project beyond the sides of the main frame are screw-threaded to receive nuts 19, and the outer ends of the rod may

be upset to lock the nuts. It will be noted that the rod 18 forms an additional brace for the main frame.

The seat frame 11 is oscillated on the rod 18. The sleeves 20 and washers 120 serve to centralize the seat frame with respect to the main frame to afford clearance between the sides of the seat frame and of the main frame for a purpose which will hereinafter appear.

Two rear legs 26, 26 are provided, each being preferably pivoted at its upper end, by rivets 27 or other suitable means, to and on the inside of a corresponding one of the two side members of the main frame 10. Each of these rear legs 26 is movable from extended position (Fig. 1) to a folded position within the bounding front and rear planes of the main frame 10 or in this specific instance to a position between the sides of the seat frame and main frame (see Figs. 6 and 7). The rear legs 26 are preferably constructed of round metallic stock suitably flattened adjacent the pivots and preferably assuming the form shown in Fig. 3 in which their lower ends are united by an integral cross member 30 to form a bail-shaped or U-shaped rear leg structure.

Means are provided whereby when either the seat structure or rear leg structure is moved from extended to folded position, or vice versa, the other of said structures is correspondingly and automatically moved. This means also preferably acts to limit the downward movement of the seat and the outward movement of the rear legs when the chair is opened. A preferred form of such means comprises loops 35 each provided with a right angled portion 36 rigidly secured, as by means of screws, nails or rivets, to a corresponding one of the side members of the seat frame 11 on the outside thereof. These loop members are preferably constructed of steel or other suitable material and each of the rear legs 26 extends through the somewhat elliptical eye of a corresponding one of said loops. The design is such that when the parts are in the occupant-supporting position the engagement of the loops with the rear legs 26 limits the downward movement of the seat to the position shown in Fig. 1 and also limits the outward movement of the rear legs 26 to the position there shown. By virtue of these above described loops, when either the seat structure 11 or the rear leg structure is moved from the position shown in Fig. 1 to that shown in Fig. 7, or vice versa, the other of said structures will be automatically and correspondingly moved to one or the other of the two positions illustrated in Figs. 1 and 7. It will be noted that each loop 35 comprises a laterally projecting pair of elements fixed to a corresponding side of the seat frame and

between which a corresponding rear leg extends.

The main frame 10 is preferably reduced at its upper portion to form shoulders 40, 40 in which the legs of an auxiliary arch 41, seat. The auxiliary arch is preferably constructed of bent-wood, i. e., a straight strip of wood bent to the form indicated, and may be glued and also screwed, or otherwise secured to the main frame 10. It will be noted that the arch 41 lies below and rearwardly of the arch 13 so as to form in conjunction therewith a comfortable back rest for an occupant of the chair.

The operation and advantages of the chair described above will now be apparent and need not be enumerated at length. It will be seen that I have provided a folding chair which is simple in construction, strong and durable, comfortable and extremely compact when folded. In folded position (Fig. 7) all of the parts of the chair lie substantially within the bounding front and rear planes of the main frame. Indeed, with the possible exception of the upholstery 17 which may be omitted if desired, all of the parts actually lie between the bounding front and rear planes of the main frame 10, when folded. And, furthermore, the upholstery 17 would be flattened or compressed, within the main frames, when the chairs are folded and piled, each on top of another, so that a large number of chairs may be stored in a small space.

Various modifications may be resorted to without departing from the scope of my invention as defined in certain of the claims of the present application. For example, the loops 35 may be replaced by two pairs of pins 135 of which each pair projects laterally from a corresponding side (see Fig. 1*) of the seat frame 11. As in the case of the loops 35 the pins 135 form a sliding connection between the seat frame and rear legs and limit the downward movement of the seat and outward movement of the rear legs. Again the cross member 30 instead of being at the lower extremities of the rear legs 26 may be placed higher, as at 130 in Fig. 3*, in which case the rear leg structure is H-shaped instead of bail-shaped. Furthermore, the main frame 10, instead of being constructed of bent-wood, may be made of two side members 110 to which a back rest 113 is suitably secured (see Fig. 3*). These and other modifications may be resorted to without departing from the scope of my invention as defined in the claims hereto appended.

In addition to advantages above set forth, it should be noted that the chair illustrated in Figs. 1, 2, 3, etc., is one which may be manufactured and assembled with great facility. The main frame, as above pointed

out, may be constructed of a single straight strip of wood bent to the U-shape illustrated. The seat frame and arch 41 may be similarly constructed. By springing the 5 sides of the seat frame apart, the seat and its upholstery may be readily inserted into the groove 15 and will then be securely held in position by the return of the sides of the seat frame to normal position. The other 10 operations in assembling the chair are so simple as not to require further explanation.

This application is a continuation of my copending application, filed July 16, 1921, Serial No. 485,246.

15 In accordance with the provisions of the patent statutes I have described the principles of operation of my invention, together with the apparatus which I now consider to represent the best embodiment thereof, but 20 I desire to have it understood that the construction shown is only illustrative and that the invention can be carried out by other means within the scope of the appended claims.

25 What I claim is—

1. The combination in a folding chair, with a main frame having uprights the upper portions of which are reduced to form shoulders and also having an arch connecting the upper reduced portions of the uprights, of an auxiliary arch arranged in parallelism to the upper reduced portions of the uprights and abutting at its ends against the said shoulders and fixedly connected to the uprights.

2. A folding chair comprising spaced uprights, a seat arranged between and pivotally connected with and spaced from the said uprights, the said pivotal connection being 40 at an intermediate point in the length of the seat, loops fixed to and extending laterally from opposite sides of the rear end portion of the seat, and rear legs extending through said loops and pivotally connected to the inner sides of the said spaced uprights.

3. A folding chair comprising in combination; a main frame having substantially straight side members, whose lower portions constitute legs, and back-rest means connecting the upper portions of said side members; a seat and means connecting the same to said main frame whereby said seat may be moved from occupant-supporting position, into said main frame; rear legs each independently pivotally connected to a corresponding one of the side members of said main frame below said back-rest means whereby said rear legs may each be moved from extended position, into said main frame 55 between the sides of the latter and said seat; and slidable means interconnecting said seat and rear legs whereby movement of said seat from extended to collapsed position imparts corresponding movement to said rear legs; the horizontal distance between the lower end of each front leg and the lower end of its corresponding rear leg being no greater than the horizontally projected distance between the upper and 60

end of each front leg and the lower end of its corresponding rear leg being no greater than the horizontally projected distance between the upper and lower ends of said main frame when the chair is in occupant-supporting position.

4. A folding chair comprising in combination; a main frame having substantially straight side members, whose lower portions constitute legs, and back-rest means connecting the upper portions of said side members; a seat frame pivoted within said main frame; rear legs pivoted within said main frame and each movable between corresponding sides of said seat frame and main frame; and a plurality of pairs of elements, each pair being rigidly secured to a corresponding one of the side members of said seat frame; each of said rear legs extending between the two elements of a corresponding pair of said elements.

5. A folding chair comprising a main frame having spaced uprights, a rigid seat arranged between said uprights and having lateral loops fixed to and extending from the outer edges of its rear portion, said loops, slightly inclined relative to the length of the seat, a transverse rod extending through the uprights and the seat and pivotally connecting the latter to the former, spacing means on said rod between the seat and the uprights and corresponding in width to the said loops, and a bail-shaped prop having side portions extended through the inclined loops on the seat and pivotally connected adjacent to their ends to the inner sides of the uprights of the main frame, said seat and bail-shaped prop movable to and from positions entirely within the plane of the spaced uprights.

6. A folding chair comprising in combination; a main frame having substantially straight side members, whose lower portions constitute legs, and back-rest means connecting the upper portions of said side members; a seat and means located between the front and rear planes of said side members and connecting the seat to said main frame whereby said seat may be moved from occupant-supporting position, into said main frame; rear legs each independently pivotally connected to a corresponding one of the side members of said main frame below said back-rest means whereby said rear legs may each be moved from extended position into said main frame between the sides of the latter and said seat; and slidable means interconnecting said seat and rear legs whereby movement of said seat from extended to collapsed position imparts corresponding movement to said rear legs; the horizontal distance between the lower end of each front leg and the lower end of its corresponding rear leg being no greater than the horizontally projected distance between the upper and 130

lower ends of said main frame when the chair is in occupant-supporting position.

7. A folding chair in which all of the parts are adapted to fold substantially within the bounding front and rear planes of the main frame and comprising in combination; a main frame having substantially straight side members, whose lower portions constitute legs, and backrest means connecting the upper portions of said side members; a seat and means connecting the same to said main frame whereby said seat may be moved from occupant-supporting position, into said main frame; rear legs each independently pivotally connected to a corresponding one of the side members of said main frame below said backrest means whereby said rear legs may each be moved from extended position, into said main frame between the sides of the latter and said seat; and means interconnecting said seat frame and rear legs whereby movement of said seat from extended to collapsed position imparts corresponding movement to said rear legs, one of said second and last named means comprising sliding connections; the horizontal distance between the lower end of each front leg and the lower end of its corresponding rear leg being no greater than the horizontally projected distance between the upper and lower ends of said main frame when the chair is in occupant-supporting position.

8. A folding chair comprising in combination, a main frame having spaced side members, whose lower portions constitute legs, and back-rest means connecting the upper portions of said side members; a seat pivoted within said main frame; rear legs pivoted within said main frame and each movable between corresponding sides of said seat and main frame; and a plurality of pairs of elements, each pair being rigidly secured to a corresponding one of the sides of said seat, each of said rear legs extending between the two elements of a corresponding pair of said elements.

9. A folding chair comprising in combination, a main frame having spaced side members, whose lower portions constitute legs, and a back-rest connecting the upper portions of said side members; a seat and means connecting the same to said main frame whereby said seat may be moved from occupant-supporting position, into said main frame, said means including pivot rod connections which extend from opposite sides of said seat into the inner sides of said main frame; rear legs each independently pivotally connected to a corresponding one of the side members of said main frame below said back-rest whereby said rear legs may each be moved from extended position, into said main frame between the sides of the latter and said seat; and slideable means interconnecting said seat and rear legs

whereby movement of said seat from extended to collapsed position imparts corresponding movement to said rear legs; the horizontal distance between the lower end of each front leg and the lower end of its corresponding rear leg being no greater than the horizontally projected distance between the upper and lower ends of said main frame when the chair is in occupant-supporting position.

10. A folding chair comprising in combination a main frame having spaced side members, whose lower portions constitute legs, and a back-rest connecting the upper portions of said side members; a seat and means connecting the same to said main frame whereby said seat may be moved from occupant-supporting position, into said main frame, said means including pivot rod connections which extend from opposite sides of said seat into the inner sides of said main frame; rear legs each independently pivotally connected to a corresponding one of the side members of said main frame below said back-rest whereby said rear legs may each be moved from extended position, into said main frame between the sides of the latter and said seat; and means interconnecting said seat frame and rear legs whereby movement of said seat from extended to collapsed position imparts corresponding movement to said rear legs, one of said first and last named means comprising sliding connections; the horizontal distance between the lower end of each front leg and the lower end of its corresponding rear leg being no greater than the horizontally projected distance between the upper and lower ends of said main frame when the chair is in occupant-supporting position.

11. A folding chair comprising in combination, a bent wood main frame whose shape is substantially that of an inverted U and whose lower ends constitute front legs of the chair, a seat, a pivot rod extending from one side of said main frame to the other and to which said seat is connected, a pair of metallic integrally connected rear legs pivoted within said main frame and each movable between corresponding sides of said seat and main frame, and sliding connections between said seat and rear legs.

12. A folding chair comprising in combination, a main frame having spaced side members, whose lower portions constitute legs, and back-rest means connecting the upper portions of said side members; a seat pivoted within said main frame; a plurality of pairs of elements, each pair being rigidly secured to a corresponding one of the sides of said seat; members adapted to extend rearwardly, each of said last named members being pivoted within said main frame, each movable between corresponding sides of said seat and main frame, and each ex-

tending between the two elements of a corresponding pair of said elements.

13. A folding chair comprising spaced uprights, a seat arranged between and pivotally connected with and spaced from said uprights, the said pivotal connection being at an intermediate point in the length of the seat, loops fixed to and extending laterally from opposite sides of the rear end portion 10 of the seat, and members extending through said loops and pivotally connected to the inner sides of the said spaced uprights.

14. A folding chair comprising in combination, a bent wood main frame whose shape 15 is substantially that of an inverted U and whose lower ends constitute front legs of the chair and the U-bend of which is adapted to be engaged by the back of a seated occupant of the chair, a seat, a pivot rod 20 extending from one side of said main frame to the other and upon which said seat is mounted, a pair of metallic rods each pivoted within said main frame and each movable between corresponding sides of said seat 25 and main frame, and sliding connections between said seat and last named rods.

15. A folding chair comprising in combination a bent wood main frame whose shape is substantially that of an inverted U and 30 whose lower ends constitute front legs of the chair, a bent wood U-shaped seat frame, a pivot rod extending from one side of said main frame through said seat frame to the other side of the main frame, a pair of 35 metallic rods each pivoted within said main frame and each movable between corresponding sides of said seat frame and main frame, and sliding connections between said seat frame and last named rods.

40 16. A folding chair comprising in combination; a main frame having spaced side members, whose lower portions constitute legs, and back-rest means connecting the upper portions of said side-members, a seat 45 pivoted within said main frame, rear legs each independently pivotally connected to a corresponding one of the side members of said main frame above the pivotal axis of said seat and each movable from extended 50 position, into said main frame between the sides of the latter and said seat; and slide- 55 able means interconnecting said seat and rear legs, the distance between said slideable means and the pivotal axis of said seat being less than one-third the distance between the 60 pivotal axis of said seat and the lower ends of the side members of the main frame; and the distance between the lower end of each front leg and the lower end of its corre- 65 sponding rear leg being no greater than the horizontally projected distance between the upper and lower ends of said main frame when the chair is in occupant-supporting position.

17. A folding chair comprising in combination, a U-shaped, bent-wood, main frame whose lower ends constitute legs; a U-shaped, bent-wood, seat frame; a pivot rod extending through the sides of said main frame and seat frame, said seat frame being 70 provided with a seat-receiving groove, a seat mounted in said groove, and rear legs movably connected to said main frame.

18. A folding chair comprising spaced uprights, a seat arranged between and pivotally connected with said uprights, the said pivotal connection being at an intermediate point in the length of the seat, loops fixed to and extending laterally from opposite sides 75 of the rear end portion of the seat, and rear legs extending through said loops and pivotally connected to said spaced uprights.

19. A folding chair comprising in combination, a main frame whose shape is that of an inverted U and whose lower ends constitute front legs of the chair, a U-shaped seat frame, a pivot rod extending from one side 80 of said main frame through said seat frame to the other side of the main frame, a pair of metallic rear legs each independently 85 pivotally connected to a corresponding one of the sides of said main frame below the curved upper portion and movable into said main frame, and sliding connections between said seat frame and last named members 90 whereby movement of said seat from extended to collapsed position imparts corresponding movement to said rear legs; the distance between the lower end of each front leg and the lower end of its corresponding rear leg 100 being no greater than the horizontally projected distance between the upper and lower ends of said main frame when the chair is 105 in occupant-supporting position.

20. A folding chair comprising in combination, a main frame whose shape is that of an inverted U and whose lower ends constitute front legs of the chair, a seat, a pivot rod extending from one side of said main frame to the other and upon which said seat is pivoted, a pair of metallic integrally connected rear legs each independently pivotally connected to a corresponding one of the sides of said main frame below the upper curved portion and movable to a position within the main frame, and sliding connections between said seat and rear legs; the distance between the lower end of each front leg and the lower end of its corresponding rear leg being no greater than the horizontally projected distance between the upper and lower ends of said main frame when the chair is in occupant-supporting position.

In testimony whereof I have hereunto affixed my signature.

CALVIN ALLEN BUFFINGTON.
